**MOP AND ADJUSTABLE HANDLE ASSEMBLY
FOR MOPS AND THE LIKE**
William Henry Richards, 1610 W. 14th St.,
Wilmington, Del.
Filed Sept. 11, 1962, Ser. No. 222,872
11 Claims. (Cl. 15—118)

This invention relates broadly to cellulose sponge mops, and more particularly to an adjustable handle assembly for mops and like implements.

An object of the invention is to provide a highly simplified, economical and efficiently operating means to facilitate rapidly adjusting a mop handle angularly, relative to the mop head, and for securely releasably locking the handle in selected adjusted positions.

Another object is to provide an adjustable handle unit which may be installed economically upon various types of mop heads, and the like.

A further object is to provide an adjustable handle assembly, including resilient means to lock a handle mounted adjusting sleeve releasably in selected positions.

Still another object is to provide a device of the mentioned character which is sturdy and durable, very easy to operate and subject to very little wear during long usage.

Other objects and advantages of the invention will be apparent during the course of the following detailed description.

In the accompanying drawings, forming a part of this application, and in which like numerals are employed to designate like parts throughout the same.

FIGURE 1 is a perspective view of a mop, partly in broken lines, having the adjustable handle assembly according to the invention applied thereto.

FIGURE 2 is a further perspective view of the handle assembly, and associated elements, partly broken away and partly in section.

FIGURE 3 is a fragmentary front elevation of the adjustable handle assembly, showing in broken lines an adjusted position of the sleeve and locking rod, and

FIGURE 4 is an enlarged central vertical section through the handle assembly, and showing in broken lines the various adjusted positions of the mop head relative to the handle.

In the drawings, wherein for the purpose of illustration is shown a preferred embodiment of the invention, the numeral 10 designates the adjustable handle assembly of the invention in its entirety, applied to a mop head 11 of any desired or conventional type. The mop head 11 may be a cellulosic sponge mop head of the foldable or nonfoldable type, as preferred, and the mop head may or may not be equipped with squeezing or wringing means, as found preferable. The mop head 11 may carry upon its upper side a suitable adaptor plate 12 as shown in the drawings, in which case the handle assembly 10 is secured to this adaptor plate. If preferred, the adaptor plate 12 may be omitted and the handle assembly 10 may be mounted directly upon a rigid backing plate carrying the cellulosic sponge.

The invention handle assembly 10 proper comprises a relatively narrow mounting plate 13, well adapted to be formed of plastics material, metal or the like. This mounting plate 13 has an integral trailing scraper extension 14, which projects rearwardly of the mop head 11 so as to serve as a floor scraper, or the like, when this is needed. The scraper extension 14 may be omitted if desired.

As shown in drawings, depicting only one preferred embodiment of the invention, the mounting plate 13 rests directly upon the flat adaptor plate 12 and is swiveled

2

thereto for horizontal angular adjustment by a suitable swivel element or screw 15, FIGURE 4, projecting upwardly through a central opening in the adaptor plate 12.

Means are provided upon the adaptor and mounting plates 12 and 13 to releasably secure these elements in one of two adjusted positions, whereby the mounting plate 13 and mop handle, to be described, extend transversely of the mop head 11, as in FIGURE 1, or longitudinally thereof, at right angles to the position shown in FIGURE 1.

Such adjusting means may comprise a pair of screw threaded openings 16 in the adaptor plate 12, spaced 90 degrees apart, and either one of which openings may receive a suitable locking screw 17, carried within an opening near the forward extremity of the mounting plate 13. Therefore, the mounting plate 13 may swing horizontally upon the adaptor plate 12 to a position at right angles to that shown in FIGURE 1, merely by retracting the screw 17 from one opening 16 and reinserting this screw in the other opening, spaced 90 degrees from the first opening. The arrangement permits the conversion of the mop depicted in FIGURE 1 to a long narrow mop, extending longitudinally of the handle, as sometimes needed to clean in narrow quarters.

If preferred, other types of adjustable connections between the adaptor plate 12 and mounting plate 13 may be utilized, in lieu of the two openings 16 and locking screw 17. For example, the mounting plate 13 could have a side extension, provided with an arcuate slot, receiving a clamping screw secured within the adaptor plate or mop head at a fixed location.

The assembly 10 further comprises a preferably metallic tubular mop handle 18, provided at its lower end with a pivot fitting 19 of plastics material, or the like, and rigidly secured thereto. The fitting 19 is disposed within a central recess 20 of the mounting plate 13, and pivoted therein by means of a transverse pivot pin 21, or the like, as shown.

Mounted slideably and telescopically upon the handle 18 is an operating sleeve 22, formed of plastics material, or the like, and being of a size for convenient grasping by one hand, when the other hand of the user is holding the mop handle 18 above the sleeve 22. The sleeve 22 has a radial opening 23 formed through its side wall, near and above its lower end. This radial opening 23 receives therethrough a short transverse locking extension 24 of a general longitudinal stiff locking rod 25, bridging the space between the sleeve 22 and the forward portion of mounting plate 13. The lower or forward end of the rod 25 is received within a narrow recess 26 near the forward end of mounting plate 13, and has a transverse pivot opening 27, adapted to register with aligned transverse pivot openings 27' in mounting plate 13, on opposite sides of the recess 26.

The pintle or hinge pin for the lower end of locking rod 25 is formed by a short integral transverse extension 28 of a generally longitudinal single wire locking spring 29 for the locking rod 25, and having at its top end an integral hook extension 30, which embraces the locking rod 25 slideably near the longitudinal center of the latter. The spring 29 may lie relatively close to the rod 25 and approximately parallel thereto, and both the locking rod and this spring extend generally longitudinally of the mop handle 18 and mounting plate 13. The spring 29 serves a dual purpose in the assembly 10, namely forming the pivot element for the locking rod 25 and also serving to resiliently bias the locking rod 25 laterally in one direction, as will be further described. The transverse extension 28 of spring 29 is also pivotally coupled to the mounting plate 13 within the pivot openings 27', whereby the spring and locking rod 25 have a common

pivotal connection with the mounting plate 13. The spring 29 is a bow-like spring which is tensioned outwardly from the rod 25, so that the latter is constantly pulled upon transversely by the hook extension 30. The pivotal connection for the lower end of the rod 25, afforded by the element 28, may be a loose connection to permit the necessary laterally swinging of the rod about its lower end, as well as the necessary free vertical swinging of this rod relative to the mounting plate 13.

To effect the actual adjustment of the mop handle 18 relative to the mop head 11, and for releasably locking these parts in at least three adjusted positions, the mop handle 18, adjacent to the shiftable sleeve 22 has a longitudinal side wall slot 31 formed therein, to receive the short locking extension 24 moveably. The slot 31 is provided at its opposite ends with short transverse branch or locking slots 32 and 33, communicating therewith, and a further transverse branch or locking slot 34 is provided intermediate the end slots 32 and 33. The extension 24 engages through the sleeve opening 23, as well as the 10 20 25 30 35 40 45 50 55 60 65 70 75 80 85 90 95 100 105 110 115 120 125 130 135 140 145 150 155 160 165 170 175 180 185 190 locking slots projecting from one side thereof and communicating therewith.

6. The invention as defined by claim 4, and wherein said spring connected with said rod includes a transverse extension pivoted to said mounting plate, said extension also forming a pivot element for said locking rod.

7. An adjustable handle assembly for mops and the like comprising a mounting plate adapted for attachment to a mop head or the like, a handle pivoted to said mounting plate and having longitudinal detent means, a locking rod engageable with said detent means, a spring engaging the locking rod and tensioned to shift the locking rod laterally in one direction toward locking engagement with said detent means of the handle, an extension on said spring pivoted to the mounting plate and said locking rod on a pivot axis spaced from and parallel to the pivot axis of the handle, and an operator slidably and rotatably mounted upon said handle and connected with the locking rod for manually shifting the latter axially and circumferentially of the handle and said detent means.

8. The invention as defined by claim 7, and wherein

20

said spring is a bow-type spring spaced from and generally parallel to said locking rod and includes a hook extension embracing said locking rod intermediate the ends of the latter.

5 9. The invention as defined by claim 7, and wherein said operator on said handle is a sleeve slidable and turnable thereon.

10 10. The invention as defined by claim 2, and a scraper extension carried by said mounting plate and projecting beyond one side of the mop head.

11. The invention as defined by claim 4, and a scraper extension secured to said mounting plate and projecting beyond corresponding sides of the mop head and adaptor plate.
